OPERATING POLE ASSEMBLY FOR
HIGH-TENSION LINES

David C. Hubbard, Centralia, Mo., assignor to
A. B. Chance Company, Centralia, Mo., a cor-
poration of Missouri

Application October 23, 1946, Serial No. 705,107

2 Claims. (Cl. 294—19)

1

The present invention relates to operating pole assemblies for high tension lines, and is particularly concerned with an improved assembly including one or more of the operating poles usually called wire tongs. Such wire tongs are employed for many different purposes, one of the principal functions of the tong being for the purpose of manipulating or moving a high tension wire away from the cross arms and insulators after the tie wire has been removed to permit the lineman to work about the upper part of the pole without danger from the high tension wires which may still be energized. Thus the wire tongs enable the lineman to work safely by using the tongs to push the wires away from the vicinity from which the workman is to operate.

The high voltage line wires are under considerable tension when installed on the poles, and the wire tongs are thus compelled to operate upon a relatively tight wire which the wire tongs must push away from the cross arm and pole, at the same time increasing the tension of the line wire. Thus it becomes necessary to exert considerable force axially on a wire tong and the assembly must have something to clamp the wire tong in place and to hold the tong in its final position with the wire pushed out of its normal position on the insulator.

For this purpose the wire tong is supported by a wire tong clamp, which is pivotally mounted upon a saddle that is secured to the line pole. In order to exert sufficient force to move the wire tong axially in its saddle some force multiplying device, such as a block and tackle, may be employed.

The assemblies of the prior art with which I am familiar applied the block and tackle in such manner that it did not act axially of the wire tong. Instead the block and tackle tended to bend the wire tong pole, and also tended to cause the wire tong pole to bind in its clamp.

One of the objects of the present invention is a provision of an improved operating pole assembly, including a block and tackle or other force multiplying means for moving a wire tong in its clamp, in which the force multiplying means is so arranged as to act in substantially an axial direction, thus eliminating as far as possible the bending moment which was placed on wire tong poles in devices of the prior art, and increasing the factor of safety for a pole of given strength and size.

Another object of the invention is the provision of an improved wire tong assembly provided with force multiplying means for acting in

2

a substantially axial direction between the clamp and the end of the wire tong, so that the wire tong may be made to slide in its clamp without binding, thus enabling the operator to accomplish his work with a lighter block and tackle or with the exertion of less effort than is necessary with the devices of the prior art.

Another object of the invention is the provision of an improved operating pole assembly which is provided with a force applying means for driving the pole in substantially an axial direction through a pole clamp, so that the pole will not be subjected to excessive wear which is otherwise encountered in devices of the prior art due to the side pull which takes place in those devices of the prior art, tending to wear off the insulating varnish and to wear and damage the protective surface of the pole.

Another object of the invention is the provision of an improved and simpler pole operating assembly, which is sturdy, adapted to be used with a minimum amount of labor, light in weight so that it can be carried by the lineman with a minimum amount of effort, and easily manipulated to actuate a wire tong when the saddle is secured to a line pole and the opposite end of the wire tong engages a line wire.

Other objects and advantages of the invention will be apparent from the following description and the accompanying drawings, in which similar characters of reference indicate similar parts throughout the several views.

Referring to the drawings accompanying the specification, of which there are four sheets, Fig. 1 is an elevational view of a high tension line with one of the line wires held by a pair of wire tong assemblies embodying the invention;

Fig. 2 is a plan view of a wire tong assembly embodying the invention;

Fig. 3 is a larger plan view of the assembly, shown without the pole and without the block and tackle;

Fig. 4 is an end elevational view of the tong clamp;

Fig. 5 is a fragmentary sectional view, taken on the plane of the line 5—5 of Fig. 4;

Fig. 6 is a bottom plan view of the device of Fig. 4;

Fig. 7 is a side elevational view, taken from the right of Fig. 4;

Fig. 8 is a side elevational view, taken from the left of Fig. 4;

Fig. 9 is a view similar to Fig. 2 of a modified wire tong assembly;

Fig. 10 is another similar view of a second modification;

Fig. 11 is a side elevational view of an anchoring device for securing one of the blocks to the end of a wire tong, as shown in Fig. 10;

Fig. 12 is a bottom plan view of the device of Fig. 11;

Fig. 13 is a sectional view, taken on the plane of the line 13-13 of Fig. 12, looking in the direction of the arrows, and showing how the ring fitting of the wire tong is secured in the device of Fig. 12;

Fig. 14 is a front elevational view of one of the clamping members of the wire tong clamp when it is equipped with an integral fitting for engaging the hook of the block, as shown in Figs. 9 and 10;

Fig. 15 is a side elevational view of this clamping member;

Fig. 16 is a top plan view of this clamping member.

Referring to Fig. 1, this is an elevational view showing one mode of use of a wire tong assembly embodying the invention. 10 indicates the line pole, which may support a pair of saddle bases 11A and 11B of the type illustrated in Fig. 1, and indicated by the numeral 11 in that figure.

The saddle bases are each secured to the pole by means of a suitable chain 12 and a suitable tightening and latching mechanism 13, Fig. 2.

Referring again to Fig. 1, each of the saddle base assemblies 11A and 11B carries a clamp 36A and 36B similar to the pole clamp 36 shown in Fig. 2 and illustrated in Figs. 3 to 8.

The two pole clamps 36A and 36B each slidably support a wire tong pole 46A and 46B. The ends of these wire tong poles carry suitable fittings engaging about the line wire 9 at substantially the same point on the wire. Thus the wire tongs 46A and 46B may be subjected to an axial push in each case, so that after the wire 9 has had its tie wire removed, the wire 9 may be pushed away from the insulator 8 and may thus leave that environment free of energized conductors for the linemen to work in comparative safety.

The tongs 46B and 46A and the line pole 10 form a triangle, and the poles must, of course, be clamped securely by means of the pole clamps 36A and 36B.

Referring now to Figs. 2 and 3, these views show in greater detail the operating tong assembly adjacent the line pole, and in addition to the elements already described they include a block and tackle for driving the wire tong axially of its clamp.

The saddle base 11 comprises a cast metal member formed with a partially cylindrical surface 14 on its base. The radius on which the surface 14 is formed may be an average radius for line poles of various diameters. The saddle base 11 preferably tapers in size from its base surface 14 to a cylindrical supporting lug 15 which is hollow, and has its end wall 16 provided with a through-bore 17.

The through-bore 17 is adapted to receive the trunnion 18 of a connecting ring swivel fitting 19, which may have a reduced threaded portion for engagement with the nut 20 located on the inside of the wall 16.

The trunnion 18 of fitting 19 carries a disk-like member 21 serving as a thrust bearing to engage the outside surface 22 of wall 16, and the disk 21 carries an outwardly projecting lug 23 which has a through-bore 24 and is partially cir-

cular in shape forming a ring to which clamps, clevises, etc., may be attached.

The saddle base 11 is provided at one side with a suitable pair of slots 25, 26 adapted to receive and anchor any of the links of the chain 12.

The other end of the chain 12 is attached by means of a pin 27 to the toggle mechanism 13, which has its other end pivotally secured by pin 28 to the saddle base 11. Mechanism 13 comprises a plurality of links or levers forming a toggle by means of which the chain may be tightened, secured and latched. For example, link 29 is pivotally secured at 28 to saddle base 11 and may consist of a pair of similar members. At its other end link 29 is pivotally secured by means of pin 30 to the handle lever 31.

Link 32 has its upper end secured to chain 12 by pin 27, and is provided with an arcuate slot 33 at its lower end for engagement with a pin 34 carried by handle lever 31. Handle lever 31 is pivotally secured to the lower link 29 at 30 as previously described, and pivotally secured to the upper link 32 by pin 34 in slot 33.

As the handle lever 31 is rotated clockwise in 32 the linkage 13 is effectively extended to release the tension on chain 12. The reverse motion of handle lever 31 in a counterclockwise direction in Fig. 3 causes this toggle to diminish its length, tighten the chain 12 and secure it when the line of centers 30-28 passes center of pin 34.

An additional safety factor is provided by the spring-pressed latch 35 pivoted on handle lever 31, and having a latching hook 36a engaging a shoulder on the link 32.

Referring to Fig. 3, the saddle support 11, is there shown pivotally supporting a clamp indicated by 36. The clamp has a pair of apertured lugs 37, 38 pivotally mounted on the bolt 39, and the bolt also supports a U-shaped clevis 40, each leg of which is apertured and supported upon bolt 39. A block and tackle has the hook 41 hooked in the clevis 40 to secure one sheave 42. The other sheave 43 has its hook 44 hooked in the ring 45 of a metal fitting secured to the end of a wire tong pole 46 (Fig. 2).

The wire tong pole extends through the clamp 36 and at its other end has a suitable tong or securing member to engage and hold an energized conductor. When the conductor has been released from its insulator, by removing the tie wire and two such assemblies, as shown in Fig. 1, engage the wire and the line pole forming a triangle, the block and tackle indicated in its entirety by 47 of either wire tong or both may be used to pull on the end of the tong, causing it to slide in the clamp 36 and pushing the energized conductor away from its insulator into such a position that the lineman may operate safely around the line pole.

It will be noted that even though the block and tackle 47 is disposed close to the wire tong 46, the block and tackle operates eccentrically with respect to the wire tong. There is a tendency of the pole to bind in the clamp and, therefore, it is of the utmost importance that the clamp be so constructed as to facilitate the sliding of the pole in the clamp with a minimum friction.

Referring now to Fig. 4, the clamp 36 preferably comprises two parts 48, 49 which are pivotally secured together by means of a pin or rivet 50. Both these members 48, 49 may comprise cast metal members made of one of the light metals such as a heat treated aluminum alloy, having particularly high physical characteristics, thereby increasing the factor of safety while still

maintaining a very light weight. It is of the utmost importance that weight be reduced to a minimum as the linemen sometimes have to carry these tools considerable distances over rough terrain and, of course, they are carried while climbing the pole.

The member 49 comprises a cast metal member having a substantially half cylindrical body 51 with an external cylindrical surface 52, and an internal cylindrical surface 53, Fig. 5. The body 51 has depending from it, in Fig. 4, a substantially rectangular lug 54 which has a longitudinally extending rectangular slot 55 forming the two legs 37 and 38 previously mentioned. These legs have the aligned bores 55a for receiving the bolt 39, and the depth of the slot 55 is sufficient to permit it to receive the swivel ring 23 when the bolt 39 passes through its bore 24.

The bores 55a extend at right angles to the axis of the cylindrical surfaces 52 and 53. Lug 54 is preferably joined to the body 51 by a pair of reenforcing ribs 56, 57, Fig. 6, and by another pair of reenforcing ribs 58 and 59 at the opposite side of lug 54.

The inner cylindrical surfaces 53 of the two clamping members 48 and 49 are substantially cylindrical throughout, and smooth and polished so as to engage the wire tong pole with a minimum amount of friction.

At each end of the body there is an outwardly curved surface 67, 68 serving to guide a pole more readily into the clamp and to prevent any excessive clamping action or marking of the pole by the end corners of the clamp.

The inner cylindrical surface 53 comprises substantially one half a cylinder for the member 49, and substantially one half a cylinder for the member 48, and the radius of these surfaces 53 is slightly larger than the radius of the tong pole 46 such as, for example, $\frac{3}{2}$ of an inch greater than the radius of the pole.

At the right side of the member 49, Fig. 6, the ribs 58 and 59 terminate in a pair of laterally projecting pivot flanges 72, 73 spaced from each other by a slot 74, and having the aligned bores 75 for receiving the rivet 76. Rivet 76 is adapted to provide a pivotal support for a screw bolt 77, the lower end of which is flattened to be received in the slot 74, rounded to rotate in the slot 74 and provided with a through-bore 78 for receiving rivet 76.

The eye bolt 77 preferably has a cylindrical shank, the upper end of which is threaded at 80 and provided with a cap nut 81 which is threaded tightly home on the end of the bolt to serve as a permanent stop. The threaded portion 80 of eye bolt 77 extends well downward on the bolt and carries a wing nut 82, which is engaged by a compression spring 83, the other end of which engages cap nut 81. Compression spring 83 engages the flat upper end 84 of wing nut 82 and serves as a nut lock, safely holding the wing nut 82 in any clamping or unclamping position.

Wing nut 82 may have a tapered frusto-conical body 85 provided with an axially threaded bore 86 and a pair of radially projecting flat wings 87 apertured at 88 to reduce the weight. At its lower end wing nut 82 has a flat annular surface 89 for effecting a clamping engagement with the upper member 48.

The two members 48, 49 are pivoted together at the left side of Fig. 4 by means of the rivet 50. In order to provide bearings for the rivet 50 the body 51 supports at its left side, in Figs. 4 and 6, a cylindrical bearing member 90 having a

through-bore 91 extending parallel to the axes of the clamp. The ribs 56 and 57 may have extensions 92, 93 around the bearing 90 reenforcing it. The length of the bearing 90, including ribs

92, 93, is sufficient to be received between a pair of bearings 94, 95 carried by the upper member 48. These bearings 94, 95 also preferably have reduced cylindrical central portions 96 and reenforcing annular ribs 97, 98 at each end.

10 The bearings 90 on the lower half project upward above the body 51 and those on the upper half 48 project downward so that when their axes are aligned their two clamping members 48, 49 form a cylindrical bore slightly larger than the pole 46.

The rivet 50 passing through all of the bearings 90, 94, 95 secures the two members 48, 49 together for pivotal movement. At its right side, Fig. 4, the upper member 48 is provided with a pair of outwardly projecting lugs 99, 100, Fig. 6, separated by a rectangular slot 101. Slot 101 is wide enough to pass the shank 79 of eye bolt 77.

Lugs 99, 100 have upper flat surfaces 102. These flat surfaces, however, are large enough only to engage the bottom annular surface 89 of wing nut 82, and each lug 99, 100 has an upwardly extending lug 103 located outside of the conical body 85 of the wing nut 82 to retain the wing nut behind them and to prevent the eye bolt 77 from pivoting out of the slot 101.

The length of the clamping members in an axial direction is substantial so that there is an elongated clamping surface of large area. When the wing nut 82 is tightened the wire tong pole 35 is securely clamped, but when the wing nut is released the pole slides freely with a minimum of damage to the surface of the pole. Thus the pole does not tend to bind in the clamp when it is being actuated by means of a block and tackle.

It will be observed that the block and tackle 40 47 has one end attached quite close to the pole 46 at the clamp 36, and the other end attached to the end of the pole 46 at the fitting 45. Thus the block and tackle is as close as it can be to the axis of the pole 46 without having the pulleys engage the pole 46.

When force is applied to the pole by means of the block and tackle this force acts in substantially an axial direction. It exerts substantially no side pull which would tend to bend or break the pole, but merely places a compression on the pole, the pole acting as a column; thus there is no tendency for the pole to bind in its clamp, but on the contrary the pole slides freely and is merely guided by the clamp during this sliding action.

55 The line wire may be pushed farther away with less effort and the block and tackle may be of lighter construction. With the devices of the prior art heavy loading tended to pull the wire 60 tong out of line, frequently bowing the lower end of the tong. With the devices of the prior art it was also difficult after the blocks had been tightened to pivot the wire tongs and the pole clamps about the saddle base.

65 With the present assembly, as the block and tackle is attached to the clamp outwardly of the pivot on the saddle base the clamp, tackle and pole still rotate freely on the saddle base after the clamp has been tightened. The block and tackle does not restrict this pivotal movement. Heavy conductors can be handled with greater ease and greater safety to the operator by means of the assembly shown, and there is less danger of breaking poles or of other accidents than with

70 75 the devices of the prior art.

Referring to Fig. 9, this is a view similar to Fig. 2 of another modified form of assembly, in which the wire tong clamp is provided with an improved structure for anchoring one of the blocks of the block and tackle. In this embodiment of the invention the upper block 43 is secured to the ring fitting 45 on the end of the wire tong 46 in the same manner as shown in Fig. 2; but the block is turned on its side so that its side engages the ring fitting 45, thus maintaining the ropes clear of the pole and its fittings.

The wire tong clamp 36 has one of its clamping members 105 of an improved construction provided with an integral extension 107 for anchoring the lower block 42 by means of its hook 41. Such a clamping member 105 is shown in Figs. 14 to 16. This clamping member may be in all ways similar to the clamping member 49, previously described, except that it is provided on one end with an integral extension 107, which may be of substantially U shape, forming a closed loop or elongated aperture 108 for receiving the hook 41 of the block 42.

As shown in Fig. 16, this extension 107 comprises a pair of legs 109, 110, which are spaced from each other substantially the same as the ribs 37, 38, which receive the pivotal connection of the saddle.

The legs 109, 110 may be relatively thin, but wide, and are joined not only to the cylindrical body 51 of the clamp, but to the ribs 37, 38, and extend diagonally outward with respect to the axis of the clamp, as shown in Fig. 15. The two legs 109, 110 are integrally joined by a yoke 111, which may be substantially cylindrical, and which is to engage the hook 41.

The diagonal arrangement of the extension 107 is adapted to space the lower block 42 from the wire tong 46 so that the pulleys or ropes will not interfere with the parts of the wire tong, but the force applied by the block and tackle is applied as close as possible to the axis of the wire tong pole, and the wire tong may be rotated on the saddle without any restraint on the block and tackle because the lower block is attached to the clamp itself.

Referring to Fig. 10, this is another modification, in which the mode of attachment of the block 42 is as shown in Fig. 9, but a special block anchor 112 is provided for the upper end of the wire tong.

This block anchor 112 is shown in Figs. 11, 12, and 13. It comprises a pair of castings 113, 114 and a threaded member 115. The casting 113 is formed with a central threaded bore 116 for receiving the threaded part of the eye bolt 115. The casting 113 has formed about the bore 116 on one side a groove 117, which is adapted to receive the ring 45 on the ring fitting of the wire tong 46.

The groove 117 is, therefore, substantially semi-circular in cross-sectional shape and annular in plan; and this portion of the casting 113 is substantially circular, except that a portion must be cut away as at 118, to provide room for the socket portion 119 of the ring fitting 45.

The circular portion of the casting 113 has a flat lateral extension 120, which extends laterally and downwardly, and which has an enlarged aperture 121 for receiving the hook of the upper block 43; and also this aperture is enlarged to reduce the weight of the assembly.

The other clamping member 114 may consist of a substantially circular disc, having a central aperture 122 for receiving the screw bolt 115, and

bordered by a depending annular flange 123 for embracing the ring 45; but here again the annular flange 123 and part of the clamping member 114 is cut away at the socket portion 118 of the ring fitting 45.

As shown in Fig. 13, the ring 45 may be placed in the groove 117, the clamping member 114 placed on top of it, and the eye screw 115 passed through the ring and through the clamping member 114 and threaded into the bore 116. The eye screw 115 has an annular shoulder 124, which engages the clamping member 114; and when the eye bolt is driven home, the ring 45 is securely clamped between the members 113, 114.

Thus, the end of the wire tong may be provided with a lateral extension for engagement with the block at this point to assure the securement of the two blocks in parallel positions with respect to the wire tong 46.

It will thus be observed that one of the common features of all of these modifications is that force is applied to the end of the wire tong in a direction parallel to the axis of the wire tong pole; and furthermore, the block being attached to the wire tong clamp outwardly of its pivot on the pole saddle, the wire tong can be rotated on the saddle or moved in any desired way on the saddle without the restraint on the block and tackle.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. An operating pole securing assembly for the application of force substantially longitudinally of the operating pole and for assisting said force comprising, a saddle and securing chain for securing the assembly to a line pole, said saddle having an outwardly projecting, round, hollow lug provided with an end wall having a circular bore, a rotatable member having a securing bolt in said bore, said rotatable member having a thrust flange engaging the end of said lug and having a pivot flange at right angles to the thrust flange and provided with a through bore, a pole clamp comprising a pair of clamping members and a securing bolt, one of said clamping members having a pair of pivot flanges located on opposite sides of the first-mentioned pivot flange, a substantially U-shaped member having its legs provided with registering bores adjacent their ends and a pintle member passing through both of said pivot flanges and through the bores in said U-shaped member, said pole clamp slidably or fixedly supporting a pole at any of a multiplicity of angles with respect to the line pole due to said pintle and pivot flanges, and said saddle and rotatable member permitting the rotation of the pole on an axis at right angles to the line pole, the U-shaped member permitting the application of force to the end of the operating pole substantially along the axis of the operating pole.

2. An operating pole assembly comprising, an elongated wooden insulating pole having a metal fixture with an eye at one end and having means for grasping a transmission line conductor at the other end, a pole clamping member comprising, a pair of cylindrical clamping jaws pivoted together and provided with an adjustable securing

bolt for slidably or fixedly supporting the operating pole, one of said clamping jaws being provided with a pivot flange, a rotatable supporting member provided with a pivot flange and a U-shaped member having registering apertures in its legs, a pintle passing through the apertures in said U-shaped member and through said pivot flanges, a force supplying tackle having one end secured to the eye on said operating pole and the other end secured to said U-shaped member for forcibly moving said operating pole longitudinally in its clamping member, a saddle supporting said rotatable member and having a laterally projecting lug with a bore receiving a trunnion carried by said rotatable member, and a chain for securing said saddle to a line pole, the operating pole being rotatable with said rotatable member to any angle relative to the axis of the line pole for engagement with a transmission line conductor, with the saddle rotated at any of a multiplicity of positions longitudinally of the line pole, and said pintle permitting the angular movement of

5

the operating pole on an axis at right angles to the axis of said rotatable member so that the operating pole may be applied to the transmission line conductor at substantially right angles to said conductor.

DAVID C. HUBBARD.
